OF HOPEDALE, MASSACHUSETTS, A CORPORATION OF MAINE.

HARNESS STOP-MOTION FOR LOOMS.

1,133,464.

Specification of Letters Patent. Patented Mar. 30, 1915.

Application filed December 20, 1913. Serial No. 307,824.

To all whom it may concern:

Be it known that I, ERASME GAGNON, a citizen of the United States, and resident of Pawtucket, county of Providence, State of Rhode Island, have invented an Improvement in Harness Stop-Motions for Looms, of which the following description, in connection with the accompanying drawing, is a specification, like characters on the drawing representing like parts.

This invention has for its object the production of means whereby the operation of a loom may be stopped automatically upon the breakage of an overhead suspending connection of any one of the series of reciprocating harness frames.

The invention provides means connected with each suspending means and released upon the breakage of any such suspending means, or upon the abnormal slackness thereof due to the breakage of any parts connected therewith, to move into a position to actuate the loom stopping mechanism.

In the present embodiment of the invention a usual form of warp stop motion is made use of for stopping the loom and is actuated for that purpose upon the breakage of a harness frame suspending means through mechanism provided by this invention.

The various novel features of my invention will appear more fully from the accompanying description and drawings and will be particularly pointed out in the appended claims.

Figure 1 is a side elevation partially in cross section and looking from the interior of the loom of so much of an ordinary form of loom as is necessary to illustrate the loom stopping mechanism and parts connected therewith; Fig. 2 is an end elevation of the loom arch and connected parts of an ordinary loom showing a preferred form of mechanism but embodying my invention in connection therewith; Fig. 3 is a plan view partially in horizontal cross-section of a portion of the construction shown in Fig. 2.

It is unnecessary to describe in detail the general features of the loom illustrated herein because the construction is a well known and familiar one. The patent to Stone No. 996,297 granted June 27, 1911, illustrates this type of loom and also the type of warp stop motion shown herein as the means for stopping the operation of the loom. The patent

to Boivert No. 794,922 granted July 18, 1905 also shows a similar type of loom and certain additional features to the usual warp stop motion which are herein made use of for convenience in connection with the present invention.

The lay 1, the cam shaft 2, the breast beam 3, the shipper 4 acting when released to throw off the power from the loom through any suitable instrumentality forming no part of the invention and not herein shown, and the remaining general features of the loom are all as shown in the aforesaid patents. So also, the warp stop motion is of the familiar type comprising the drop devices or detectors 5, each suspended from a warp thread and descending into the lowermost position by failure or undue slackness of its warp thread, the double feeler 6 carried by the rock shaft 7 and normally vibrated back and forth below the ends of the detectors, the cam 8 on the shaft 2 for vibrating the feeler 6 through the medium of the links 9, the arms 10 and the follower 11 pivoted at 12 on the hooked link 13, the tappets 14 on the cam shaft 2 all operating as described in the aforesaid patents.

I have shown the loom as provided with four harness frames, but it is obvious that the invention is equally applicable to any number. These harness frames 15 may be of any usual construction and provided with any of the usual forms of heddles. So also they may be operated in any suitable manner. The operating connections for drawing the frames down are not illustrated, but the suspending means or connections of a preferred and usual form are shown in Fig. 2. In this form the loom arch 16 is provided with upwardly extending brackets 17, 18 in which are journaled rollers or pulleys 19, 20, one in each bracket for each harness frame, while in the bracket 18 are also mounted cam shaped pulleys 21, one for each harness frame. The flexible connections 100 forming the part of the suspending means are shown as the usual straps 22 adjustably connected by hooked bars 23 near each end of the frame, extending up over the pulleys 19 and 20, and then united as by the hook 24 105 and passing around the pulley 21 and connected by another hooked bar 25 to a coiled spring 26 having a metal loop 27 at its end engaging a lug 28 on the bracket 17. Similar connections are provided for each harness 110

frame and with the usual adjustable sections 29. In the operation of the harness frames the lower portion of each frame is usually connected to and operated from cams on the 5 cam shaft, as, for example, as shown in the patent to Whitehead No. 996,725, granted August 9th, 1910, so that at the required times to form the proper shed the proper harness frames are depressed. This action 10 takes place against the action of the suspending means which in turn act to lift and restore the harness frames to uppermost position. The suspending means herein shown are provided with the coil springs 26 which 15 are thus always under tension and act to raise or lift the harness frames.

It not infrequently happens that the connections to one or the other of the harness frames break, particularly the suspending 20 connections. When this happens the corresponding harness member drops at either one or both ends, and if not discovered promptly and the loom stopped, very serious warp and other breakage may occur. In 25 this invention the breakage or abnormal slackening of the suspending connections is made use of to release connections which act to stop the loom. In the particular form illustrated for this purpose the loop 27 at 30 the end of each suspending means is made considerably longer than the lug 28. When the parts are in proper working order the harness frames will through the springs 26 hold the outer end of each loop 27 up against 35 the outer end of each lug 28, as shown in Fig. 2. If now any suspending connection breaks at either end of any harness frame, or if any connection acting to draw any frame downward breaks, the corresponding loop 27 40 at the end of the connection will be released and will either have or will be capable of having a movement to the left, viewing Fig. 2, to the extent of the difference in length between the slot in the loop 27 and the lug 45 28. This movement is made use of herein for effecting the stoppage of the loom. For this purpose a plate 30 is secured to and projects from the bracket 17. Bearing pins or 50 shafts 31 project from this plate one for each bank of harness frames. In the arrangement shown there are two banks of harness frames, and consequently two shafts 31. On each shaft 31 is mounted a bell crank lever 32 for each suspending means of 55 the harness frame in its bank. In the construction illustrated there are four harness frames, two in the upper bank and two in the lower, and consequently, there are two bell crank levers 32 pivoted on each shaft 31. 60 Each bell crank lever is normally moved by a coil spring 33 connected to one of two pins 34 projecting outwardly from the plate 30. These bell crank levers constitute actuators and are positively moved by the springs 33. 65 These actuators, it will be observed thus

have their movement with respect to or relatively to the corresponding frame and suspending means. Each actuator is connected with its corresponding harness frame suspending means and by it held against movement. In the construction illustrated this is secured by forming an eye 35 on the end of each loop 27 and through this eye the corresponding short arm of the actuator 32 projects. It will thus be seen that the parts are 70 normally held in the position shown in Fig. 2. If now any suspending means breaks or becomes abnormally slackened it releases its corresponding actuator which thereupon is positively moved by means of its corresponding spring into abnormal position. Each of these actuators is arranged to effect the stopping of the loom when thus moved, and this result is secured preferably by the construction illustrated. On the loom arch at 36 is 75 pivoted a trigger device, the shorter arm 37 of which extends horizontally and the longer arm of which 38 projects downwardly adjacent to a vertical rod 39 having an offset end 40, and pivotally connected at 41 to, and 80 consequently vertically reciprocated by, the vibrating feeler 6. This rod 39 may be and for convenience is the same as that shown in the patent to Boivert previously referred to, and may have the same functions in the 85 loom. Each actuator 32 has pivotally connected therewith a plunger 42 guided in a bracket 43 projecting from the loom frame and presenting a bent end 44 which when the parts are in normal position rests against 90 the arm 37 of the trigger and holds the trigger in inactive position, as shown in Fig. 2. But whenever any actuator 32 is released its corresponding plunger 42 is depressed and the trigger is swung carrying the arm 38 100 into the path of the end 40 of the rod 39. The arm 38 is provided with a hooked shaped end 45 which immediately catches upon the end 40 of the rod 39, and locks that rod against movement, and consequently 110 locks the warp stop motion in the same manner as if it had been locked by one of the detectors 40, and consequently the stopping of the loom is at once effected.

For convenience of construction the trigger device is shown as made in separate parts. The short arm 37 is secured at one end to the pivotal shaft 36 and the long arm 38 to the other end of this shaft and the shaft itself which forms the pivot of the 115 trigger is journaled in a bearing bracket 46 secured at 47 to the face of the arch. This enables the long arm of the trigger to be positioned readily in the path of the rod 39.

It will be seen that the invention is not 120 dependent upon the particular form of connections or suspending means for the harness frames nor upon the particular construction of loom stopping mechanism and that varying changes or modifications may 125 130

be made by those skilled in the art without departing from the spirit and scope of the invention as set forth in the annexed claims.

Having fully described my invention, what I claim as new and desire to secure by Letters Patent is:

1. In a loom, the combination of a plurality of reciprocating harness frames each having overhead lifting and suspending means, a warp stop motion including a vibrating feeler, a vertically movable rod connected with the vibrating feeler, a trigger normally out of, but when moved into, the path of said rod acting to lock the rod against movement and so through the medium of the warp stop motion to stop the loom, an actuator for each suspending means cooperating with said trigger, and means released by the breakage of a suspending means to move its corresponding actuator and cause it to swing the trigger into the path of said rod.

2. A loom comprising a plurality of reciprocating harness frames each having overhead lifting and suspending means, loom stopping mechanism, and spring actuated means mounted for movement with respect to each frame and suspending means and released upon the breakage or abnormal slackness of the suspending means to move under its spring actuation into a position to actuate the loom stopping mechanism.

3. A loom comprising a plurality of reciprocating harness frames each having overhead lifting and suspending means, loom stopping mechanism, and means mounted for movement with respect to each frame and suspending means and held out of actuating position by connections to each suspending means and acting when released to move into a position to actuate the loom stopping mechanism.

4. In a loom comprising a plurality of reciprocating harness frames each having overhead lifting and suspending means, a warp stop motion including a vibrating

feeler, an element connected to and vibrating with said feeler and spring actuated means connected with each suspending means and released upon the breakage thereof to move into the path of said vibrating element, and thus cause the stopping of the loom.

5. In a loom the combination of a plurality of reciprocating harness frames each having overhead lifting and suspending means, a plurality of normally quiescent actuators one connected with each suspending means and mounted for movement with respect to said suspending means and its frame and moved upon the breakage of said suspending means into actuating position, loom stopping means, and means for actuating said loom stopping means to stop the loom operated by the movement of any actuator into actuating position.

6. In a loom a plurality of reciprocating harness frames each having overhead lifting and suspending connections terminating in a loop, lugs to receive and hold said loops and of materially less length than the loops whereby upon the breakage of any connection the corresponding loop may move with respect to its lug, an actuator pivotally mounted adjacent each loop, a spring acting to draw the actuator away from the loop, connections between the loop and actuator normally to hold the spring under tension, a loom stopping mechanism including a vibrating element, a trigger and connections between said trigger and each of said actuators whereby upon the breakage of either suspending connection the corresponding actuator moved by its spring will throw the trigger into the path of said vibrating element and stop the loom.

In testimony whereof, I have signed my name to this specification in the presence of two subscribing witnesses.

ERASME GAGNON.
